S. S. VAN KEUREN,
AERIAL TORPEDO.
APPLICATION FILED FEB. 12, 1916.

1,191,374.

Patented July 18, 1916.

Attorney

UNITED STATES PATENT OFFICE.

SYLVANUS S. VAN KEUREN, OF ABERDEEN, SOUTH DAKOTA.

AERIAL TORPEDO.

1,191,374.

Specification of Letters Patent. Patented July 18, 1916.

Application filed February 12, 1916. Serial No. 78,049.

To all whom it may concern:

Be it known that I, SYLVANUS S. VAN KEUREN, a citizen of the United States, residing at Aberdeen, in the county of Brown 5 and State of South Dakota, have invented certain new and useful Improvements in Aerial Torpedoes, of which the following is a specification, reference being had to the accompanying drawings.

10 My invention relates to projectiles, and particularly to torpedoes adapted to be dropped from flying machines.

The general object of my invention is the provision of a torpedo so constructed that 15 it will fall from a flying machine with the minimum of deflection and with a certainty that the end of the torpedo having the firing pin therein will strike first.

A further object of my invention is the provision of a torpedo including a chamber containing a bursting charge and an outer chamber surrounding the inner chamber and adapted to contain bullets or other projectiles, and also adapted to be filled with 25 inflammable fluid, the fluid filling the interstices between the projectiles in the chamber.

Still another object of my invention is to provide means for preventing the accidental projection of the firing pin against the charge igniting cap or fulminate.

Other objects will appear in the course of the following description.

My invention is illustrated in the accompanying drawings, wherein:

Figure 1 is an elevation of a torpedo constructed in accordance with my invention; Fig. 2 is a like view to Fig. 1, but partially in section; Fig. 3 is a transverse section on 40 the line 3—3 of Fig. 1; Fig. 4 is a fragmentary sectional view of the lower end of the torpedo, the firing plug and the safety cap.

Referring to these figures, 10 designates a 45 cylindrical body, this body being hollow to provide an inner chamber 11 for containing a bursting charge of any suitable explosive. The body of the torpedo is conical at its lower end and the chamber 11 is also 50 conical at its lower end. Surrounding the chamber 11 is an annular chamber 12 which opens at its upper end upon the inside face of a screw threaded tapering bore 13 in which a breech plug 14 is adapted to be 55 screwed or otherwise fastened. The chamber 12 is also formed with branch inlets 15

normally closed by plugs 16 and by which inflammable liquid such as high test gasoline or bisulfid of carbon may be filled into the chamber 12.

60 The breech plug 14 is tapering in form to fit the bore 13, and on its periphery is formed with relatively deep screw threads engaging the screw threads on the bore 13. Extending from the breech plug and having screw threaded engagement therewith is a post 17 terminating at its upper end in an eye 18. Mounted upon the post in any suitable manner are the spiral blades 19. I have illustrated four of these blades and 70 each blade as having a quarter turn. The rear ends of two of these blades are considerably broadened while the forward ends of the other blades are relatively broad. The blades are held in place on the post or 75 member 17 by means of bands 20, the blades being disposed in slots in the post and the bands holding the blades in place.

The lower or tapering end of the torpedo is formed with the bore 21 which is screw 80 threaded for engagement with a tapering firing plug 22. This plug is hollow and at its inner end is formed with an orifice 23 entering the hollow interior of the plug. Inward of this orifice there is provided a 85 seat 24 for a cap or other detonator. The outer or larger end of the plug is formed with a circular head 25 screw threaded for engagement by a safety cap 26. Disposed within the hollow interior of the plug and 90 longitudinally movable therein is a firing pin 27. This pin is slotted and a guide pin 28 extends through the slot and permits longitudinal movement of the firing pin while preventing it from falling out of the torpedo. The end of the firing pin is formed with a head 30 and a spring 31 urges the firing pin outward and away from the detonator supported on the seat 24. A safety key 32 is adapted to be inserted between the 100 head 30 and the head 25 and when it is in position is of course inclosed within the cap 26. When the cap 26 is removed, however, this key may be withdrawn, whereupon the torpedo will be in condition for use.

105 As before stated, the chamber 11 is intended to be filled with a bursting charge ignited by the engagement of the firing pin with the cap or detonator. The chamber 12 is intended to be filled with bullets, scrap 110 iron or other projectiles, these projectiles being filled into the chamber 12 through the

openings which terminate on the bore 13, and after the projectiles are in place the interstices between the projectiles are to be filled with inflammable liquid such as high 5 test gasoline. This liquid may be filled in through the branches 15 which may be afterward closed by the plugs. The torpedo is now ready for use. It is intended to be dropped from an aeroplane, Zeppelin or 10 other airship, and the fixed spiral blades 19 will give it a rotation around its longitudinal axis so that the torpedo will fall straight to its mark with a minimum of deviation or deflection. Thus the torpedo revolves in its 15 flight as does a rifle bullet and by so doing it will be prevented from any rotatory movement around a shorter axis and will be projected point foremost.

The mechanism for projecting or dropping 20 the torpedo forms the subject-matter of a separate application executed of even date herewith.

Having described my invention, what I 25 claim is:

1. In a torpedo of the character described, a body having a firing plug formed with a longitudinal bore, a seat for a detonator and an exterior head, a firing pin longitudinally movable in the plug and having a

head, a spring between the head of the firing pin and the head of the plug, a safety key disposed between the head of the plug and the head of the firing pin and a detachable cap inclosing the head of the firing pin and the key. 30

2. In an aerial torpedo of the character described, a body having a relatively heavy nose, the nose being longitudinally bored and the bore being screw threaded and tapering, a tapering firing plug having screw 40 threaded engagement with the bore of the nose and also formed with a longitudinal bore and with a seat for a detonator and with an exteriorly screw threaded head, a spring resisting the inward movement of the 45 firing pin, the inner face of the head of the firing pin and the outer face of the head of the plug having transversely extending registering grooves, and a safety key removably disposed in said grooves and holding the 50 firing pin from inward movement.

In testimony whereof I hereunto affix my signature in the presence of two witnesses.

SYLVANUS S. VAN KEUREN.

Witnesses:

C. G. ANDERSON,
J. C. McINTYRE.
